INVENTOR

BY *Victor J. Evans*

ATTORNEY

UNITED STATES PATENT OFFICE.

THOMAS LESTER BELL, OF GARTH, KENTUCKY.

DRILL HEAD.

Application filed December 12, 1925. Serial No. 75,069.

This invention relates to drill heads, and contemplates a novel construction and arrangement of parts wherein the drill bits can be quickly and conveniently associated with or removed from the head as the occasion may require, the invention residing in the construction, combination and arrangement of parts as claimed.

In the drawings forming part of this application, like numerals of reference indicate similar parts throughout the several views, and wherein:

Figure 1 is a view in elevation of the drill head complete.

Figure 2 is a sectional view on line 2—2 of Figure 1.

Figure 3 is a fragmentary view of the shaft.

Figure 4 is an end elevation thereof.

Referring to the drawings in detail, 10 indicates a sleeve which may be constructed from any suitable material and vary in size without departing from the inventive idea, and adapted to receive the shaft 11 of a length substantially equal to that of the sleeve 10. The shaft is provided with a flange 12 at one end thereof and adapted to bear against the adjacent end of the sleeve 10 when the parts are associated, as shown in Figures 1 and 2. The shaft is provided with a plurality of spaced longitudinal grooves, arranged in pairs, one pair of grooves being indicated at 13, while the other pair of grooves are indicated at 14.

The grooves of each pair are diametrically opposite each other, and as clearly illustrated in Figure 2 the grooves 13 are comparatively short when considered with relation to the length of the grooves 14. All of the grooves, however, open at one end of the shaft, and are in a line with notches 15 formed in the flange 12, as shown in Figure 4. Each groove is formed at its inner end to provide a rounded portion 16 to accommodate the head 17 of a drill bit 18, there being one of these bits arranged in each groove. The bits arranged in the grooves 14 extend an appreciable distance beyond the outer ends of the bits arranged in the grooves 13.

The longer bits 18 constitute leaders for the shorter bits or reamers, while the sleeve 10 is provided with a spiral flange 19 for removing the dust or the like from the hole being bored by the tool, the invention being

primarily intended for use by coal miners, 55 although its general application is contemplated by the claims. The shaft 11 is slotted at one end, as at 20, to receive the adjacent end of the power or drill shaft (not shown), these parts as well as the sleeve 10 being held 60 together by means of a bolt 21 having associated therewith a nut 22. It is manifest that should any one or more of the bits 18 become broken, it can be quickly and conveniently replaced by a new bit with a saving of time and money as compared with the character of drill now generally employed.

While it is believed that from the foregoing description the nature and advantages of the invention will be readily apparent, I 70 desire to have it understood that I do not limit myself to what is herein shown and described, and that such changes may be made when desired as fall within the scope of what is claimed.

Having thus described the invention, what is claimed as new, is:

1. In combination, a sleeve, a shaft arranged therein and having spaced longitudinal grooves, a flange on one end of the shaft and adapted to bear against the adjacent end of the sleeve, and having notches in a line with said grooves, drill bits arranged in said groove and clamped between the shaft and sleeve, and means for securing the 85 sleeve and shaft together.

2. In combination, a shaft having spaced longitudinal grooves therein, a flange at one end of the shaft and having notches in a line with said grooves, drill bits arranged 90 in said grooves and passed through said notches, a sleeve surrounding said shaft and holding said bits associated therewith, means for holding the sleeve and shaft together, a spiral flange surrounding said sleeve, and 95 said bits being of relatively different lengths.

3. In combination, a shaft having spaced longitudinal slots arranged in pairs, the slots of one pair being shorter than the slots of the other pair, bits of relatively differer 100 lengths arranged in the respective slots, a sleeve surrounding the shaft and holding the bits associated with the latter, said shaft having a slot at one end, and a bolt passed through the slot and connecting the shaft 105 and sleeve together for the purpose specified.

In testimony whereof I affix my signature.

THOMAS LESTER BELL.
